(57) **CLAIM**

The ornamental design for a cabinet bar pull, as shown and described.

DESCRIPTION

FIG. 1 is a top perspective view of a cabinet bar pull showing my new design.

FIG. 2 is a front view of the cabinet bar pull.

FIG. 3 is a rear view of the cabinet bar pull.

FIG. 4 is a left side view of the cabinet bar pull.

FIG. 5 is a right side view of the cabinet bar pull.

FIG. 6 is a top view of the cabinet bar pull.

FIG. 7 is a bottom view of the cabinet bar pull; and,

FIG. 8 is a bottom perspective view of the cabinet bar pull. The contour shading shown represents surface contours, not features, of the cabinet bar pull.
